[57] CLAIM

The ornamental design for an air freshner or similar article, substantially as shown and described.

DESCRIPTION

FIG. 1 is a perspective view of an air freshner or similar article showing my new design;
 FIG. 2 is a top plan view thereof;
 FIG. 3 is a bottom plan view thereof;
 FIG. 4 is a side elevational view thereof;
 FIG. 5 is another side elevational view taken 90 degrees from FIG. 4; and
 FIG. 6 is third side elevational view showing the detachable pin in its position of use.

*Fig. 3**Fig. 1**Fig. 2**Fig. 4**Fig. 5**Fig. 6*
